Charlie A. Pendleton, INVENTOR.

BY

Geo. P. Kimmel.

ATTORNEY.

UNITED STATES PATENT OFFICE.

CHARLIE A. PENDLETON, OF CRAMERTON, NORTH CAROLINA.

FUSE PULLER.

Application filed February 2, 1926. Serial No. 85,596.

This invention relates to electric fuse handling devices and pertains particularly to fuse pulling and placing tongs.

The primary object of this invention is the provision, in a manner as hereinafter set forth, of an improved fuse handling tool perfectly insulated against the passage of an electric current from the fuse point to the hand of the person holding the fuse gripper.

Another object is the provision, in a manner as hereinafter set forth, of fuse handling tongs of strong and durable construction, light in weight, designed to give perfect safety to the user and inexpensive to manufacture.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features of the invention as expressed in the appended claims.

In the drawing:—

Figure 1 shows the tool embodying this invention, in side elevation, with parts thereof broken away to show details of construction.

Figure 2 shows an edge view of the tool. Referring now to the drawing in detail wherein like numerals of reference indicate corresponding parts throughout the several views, the fuse handling tool embodying this invention comprises two main portions, namely, a stationary portion indicated generally by the numeral 1 and a movable portion indicated generally by the numeral 2.

The stationary portion constitutes the stock of the tool and includes a one-piece coupling member consisting of tubular forward and rear end portions 3, 4 respectively, and a cylindrical intermediate portion 5. The inner diameter of the tubular portion 3 gradually decreases from its forward to its rear end and the inner diameter of the tubular portion 4 gradually increases from its rear towards its forward end. Each of said end portions is termed a sleeve. The intermediate portion 5 is provided with a diametrically extending slot 6 which is disposed lengthwise thereof. The rear end of the sleeve 3 is integral with the forward end

of the intermediate portion 5 and opens into the slot 6. The forward end of the sleeve 4 is integral with the rear end of the intermediate portion 5 and opens into the slot 6.

Extending into, as well as fitting the sleeve 4, is the tapered reduced forward end portion 7, of a handle body 8, formed of wood or other appropriate insulation material. A holdfast device 9 is employed for securing the reduced portion 7 to the sleeve 4.

The stationary portion or stock of the tool further includes a solid one-piece connecting member formed of insulation material and comprising a cylindrical intermediate portion 11 and tapered front and rear end portions 13, 10 respectively. The end portion 10 is fitted in the sleeve 3 and is secured therewith by a pin or holdfast device 12. The forward end of the sleeve 3 abuts against the rear end of the intermediate portion 11.

Secured to the connecting member is a one-piece head element comprising a cylindrical intermediate portion or neck 15, a forward end portion or head 16 and a tubular rear end portion or sleeve 14. The head 16 is disposed diametrically of the neck 15. The head 16 projects at right angles to the neck 15 and one end of the head 16 extends a greater distance laterally from the neck 15 than the other end of the head 16. Integral with that end of the head 16, which projects a greater distance from the neck 15, and disposed substantially at right angles to the head 16, is a forwardly extending stationary jaw 18 having the forward portion of its inner face of slightly arcuate shape, as at 19, and the rear portion of its inner face in the form of a transversely extending semicircular groove 20. The head 16 offsets the jaw 18 with respect to the neck 15 and the latter is formed with a lengthwise extending slot 17.

The head 16 has extending centrally from the other end thereof an ear 21 which is of materially less width than the head for the reason and purpose about to be set forth.

The handle body 8 is termed an inner insulating member and the solid one-piece connecting member an outer insulating member and said members are connected together and maintained in spaced relation by the slotted one-piece coupling member.

The shiftable portion 2 of the tongs comprises a pivoted spring controlled handle sleeve 22 having a flat inner face 23 and a substantially semicircular outer face. This

sleeve is adapted to receive in its rear end the reduced forward end portion 24, of an oscillatory handle 25, formed of a body of insulating material. A retaining pin 26 is 5 passed through the reduced portion 24 and the sleeve 22 to retain the parts in permanent engagement.

The forward end of the handle sleeve 22 has projecting from opposite sides thereof 10 the ears 27 and 28, respectively, the ear 28 which is upon the inner face of the sleeve, is, as shown, relatively long and adapted to extend into and to the far side of the slot 6 in the intermediate portion 5 15 of the coupling member 1. A pivot pin 29 is passed through the said intermediate portion 5 and the inner end of this ear 28, to pivotally connect the ear thereto, thus mounting the handle portion 25, in a manner 20 as to enable it to be swung inwardly and outwardly toward and away from the stationary handle portion 8. A spring member 30 is interposed between the face 23 and the adjacent portion of the sleeve 4, to maintain the oscillating handle 25 in outwardly 25 swung position, under all normal conditions.

Mounted upon the ear 21 is an oscillating jaw member 31, which opposes the jaw 18 and has the forward portion of its inner face of arcuate contour similar to the portion 19 of the jaw 18, as indicated at 32. The rear portion of the inner face of the jaw 31 is provided with a substantially semi-circular transverse slot 33, in the same 35 manner as the rear portion of the inner face of the jaw 18.

Formed integral with the rear end of the jaw 31, is a shank 36, provided with a lengthwise disposed slot 34, into which the 40 ear 21 is extended. Fixed to the shank 36 is a pivot pin 35, which extends through the ear 21 and which provides for the swinging of the jaw 31, towards and from the stationary jaw 18.

45 Formed integral with the rear end of the shank 36 and extending at right angles thereto, is an arm 37, which projects through the slot 17 in the neck portion 15. As shown the free end of this arm 37 extends beyond the other side of the neck portion 15 and abuts the underside of the head 16 when the jaw 31 is swung outwardly. The shank 36 and arm 37 provides, as a part of the shiftable jaw, a bell crank. Interposed between the free outer end of the arm 37 and the ear 27, upon the oscillating handle member 25, is a connecting link formed in three portions, namely, the end connecting portions 38 and 39, respectively, 50 and the intermediate portion 40 which is formed of an insulating material. The end portions 38 and 39 are pivotally connected to their respective associated swinging members by means of the pivot pins 41 and 42, while the intermediate insulating por-

tion 40 has its ends threaded into the opposed ends of the members 38 and 39 as is shown in Figure 1.

From the foregoing description it will be readily seen that the metal parts of the head and jaw members are separated from the metal sleeves 3, 4 and 22 by means of the insulating members 11 and 40 and it will therefore be readily apparent that fuses of all types can be safely handled for no current can pass through the tongs to the hand of the user.

It will also be seen that upon compressing the handle portions 8 and 25, the portion 25 of the handle will be swung inwardly toward the portion 8, against the tension of the spring 30 thus drawing upon the link 40 and the arm 37 to swing the oscillating jaw 31 inwardly toward the stationary jaw 18. A secure and powerful grip can thus be obtained upon any fuse for the safe removal or replacement of the same. Upon the release of the portion 25 the spring 30 will act to swing the handle 25 outwardly away from the handle 8 thus pushing up upon the link 40 and opening the jaws of the tongs.

Having thus described my invention what I claim is:

1. In a tool of the character described, a handle, a jaw member, said jaw member formed at its rear end with one end of a head disposed at right angles to and connected to the forward end of the handle and providing for the offsetting of said jaw member laterally with respect to said end of the handle, a co-operating jaw member pivotally connected to the other end of said head, and spring controlled means connected with said pivoted jaw and with the handle for actuating the pivoted jaw relative to the jaw member.

2. In a tool of the character described, a handle, a head connected to the forward end of the handle and projecting laterally from opposite sides of each end, a stationary jaw having its rear end integral with one end of said head and offset a considerable distance with respect to the handle, a shiftable jaw pivotally connected to the other end of the head, offset with respect to the handle and opposing said stationary jaw, said shiftable jaw having as a part thereof a bell crank having one of its arms extending transversely of and through the handle adjacent to said head, and shifting means for said shiftable jaw, said means connected with the free end of the handle and with said arm.

3. A fuse puller comprising a stock formed with an opening intermediate its ends, a neck fixedly secured to the outer end of the stock and formed with a slot, a head integral with the neck and further projecting from opposite sides of the latter, a stationary jaw integral with one end of the

head, a movable jaw pivotally connected to the other end of the head and including a bell crank having one of its arms extending through said slot, and shifting means for 5 the movable jaw pivotally connected at one end to said arm and intermediate its ends to said stock within said opening.

4. A fuse puller comprising a stock formed with an opening intermediate its ends, a neck fixedly secured to the outer end of the stock and formed with a slot, a head integral with the neck and further projecting from opposite sides of the latter, a stationary jaw integral with one end of the 15 head, a movable jaw pivotally connected to the other end of the head and including a bell crank having one of its arms extending through said slot, shifting means for the movable jaw pivotally connected at one end 20 to said arm and intermediate its ends to said stock within said opening, and a controlling spring for said shifting means, said controlling means positioned rearwardly of said opening and seated in said shifting means 25 and stock.

5. In a fuse puller, a pair of spaced, lengthwise opposed insulating members, a coupling member secured to and maintaining said insulating members in spaced relation and provided with an opening, a neck secured to one of the insulating members and provided with a slot, a head connected to the outer end of the neck and projecting from opposite sides thereof, a stationary jaw 30 integral with one end of said head, a movable jaw pivotally connected to the other end of said head and including a bell crank having one of its arms extending through said 35

slot, and movable jaw shifting means pivotally connected at one end to said arm and 40 intermediate its ends to said coupling member within said slot, said shifting means including an insulating part opposing that insulating member free of the neck.

6. In a fuse puller an inner and an outer 45 insulating member arranged in lengthwise opposed relation and spaced from each other, a coupling member mounted on the opposed ends of said insulating members, secured therewith and maintaining them in spaced 50 relation, said coupling member formed with an opening positioned between said insulating members, a neck secured to the outer insulating member and provided with a slot, a head integral with the outer end of the 55 neck and projecting from opposite sides thereof, a stationary jaw integral with one end of said head, a movable jaw pivotally connected to the other end of said head and including a bell crank having one of its 60 arms extending through said slot, and movable jaw shifting means having one end pivotally connected to the free end of said arm and further including means extending into said opening and pivotally connected to 65 said coupling member, said shifting means further including an insulating part opposing said inner insulating member, and a coiled controlling spring interposed between 70 said coupling member and said shifting means rearwardly with respect to said opening.

In testimony whereof, I affix my signature hereto.

CHARLIE A. PENDLETON.
